UNITED STATES PATENT OFFICE.

NATHAN E. NASH, OF WESTERLY, RHODE ISLAND, ASSIGNOR OF ONE-HALF
TO ROBERT H. STALEY, OF JERSEY CITY, NEW JERSEY.

GAS-ENGINE.

SPECIFICATION forming part of Letters Patent No. 340,453, dated April 20, 1886.

Application filed October 12, 1885. Serial No. 179,639. (No model.)

To all whom it may concern:

Be it known that I, NATHAN E. NASH, of Westerly, in the county of Washington and State of Rhode Island, have invented certain 5 Improvements in Gas-Engines, of which the following is a specification.

This invention relates to certain improvements in that class of engines in which the moving parts are primarily operated by the 10 ignition of an explosive body, such as gunpowder or the vapor of hydrocarbon and air.

In the drawings forming a part hereof, Figure I is a partly-sectional side view of the engine. Fig. II is a section taken on the dotted line X X, Fig. I. Fig. III is a plan of the 15 engine.

A is the casing of the engine, of such shape as will admit of the joint rotation of the pistons A' and B therein. These pistons are cylindrical blocks secured to shafts a a', the upper one of which, a, projects through a stuffing-box, b, on one side of the casing A. The lower shaft, a', extends through stuffing-boxes b' and c in the sides of the casing, and one end 20 of the shaft is used to perform work, while the other is connected to the shaft a by means of gears B' and C, for purposes hereinafter described.

The pistons A' and B consist of cylindrical 30 blocks, as before stated, and each one has four teeth on its periphery, which are denoted by c', and they are at equal distances apart, and at each side of each tooth is a depression, d, to admit of the rotation of the pistons, as will be 35 understood by reference to Fig. I of the drawings.

In order that the teeth of the pistons may always register or continue in gear, the shafts a and a' are connected by the gears B' and C, 40 as before stated. C' and D are channels having branches d', e, e', and f, which extend to the interior of the casing and between the pistons A' and B. The channels C' and D are united to the valve-chambers D' and E by 45 means of pipes E', F, F', and G, which can be either bolted to the casing or cast as a portion thereof. G' and H are respectively the admission and the exhaust valves, situated relatively in the valve-chambers D' and E. The

admission-valve chest is in communication 50 with the explosion-chamber H' by means of the port f'.

In the further description of the invention which follows it will be supposed that the explosive mixture used is the vapor of hydrocarbon fluid and the proper proportion of atmospheric air. The fluid required as an element of the explosive mixture is introduced to the explosion-chamber at intervals or intermittently, and the means employed consist 55 of as follows: A vapor-duct, g, formed in the wall of the explosion-chamber is supplied with the fluid from a suitable pipe, g', and it terminates near the bottom of the said chamber. In this duct are situated the valves h and h', which 60 are separated, so as to hold in the portion of the duct between them the proper charge of fluid. The action of these valves will be hereinafter more fully described.

I is an air-pump to force air to the explosion-chamber, and it is in communication with the duct g and the interior of the explosion-chamber by means of the opening i.

I' is an air-exhaust pump to effect the ignition of the explosive mixture in the chamber 75 H', and to this end there are two orifices, i' and j, which connect the pump with the interior of the explosion-chamber, and a third one, j', having a check-valve, k, opening inwardly, through which the flame k' is drawn 80 to the interior of the said exhaust-pump.

The pistons J J' of the pumps I and I' have rods which pass through stuffing-boxes in the heads of the said pumps, and these rods are united by proper joints to a lever, K, pivoted 85 at one end to the vibratory bar K', which in turn is pivoted to a bracket, l, projecting from the pipe F, or any stationary part of the machine. This lever K' is vibrated from the lower gear, C, through the medium of the pinion L on the shaft L', and crank-wheel M, having a pin, l', a rod, m, arms m' and n on the shaft n', and the link o, which connects the arm n with the end of the said lever. The pinion L is one-fourth the diameter of the wheel C. 90 Consequently the pistons of the air-pumps make four double strokes to one revolution of the shafts a and a'. The valves h and h' have

arms o' and p , which are connected by a rod, p' , and the upper one is attached to the lever K by means of a link, q , and a stud, q' .

The admission and exhaust valves G' and H are fastened to shafts r and r' , having arms M' and N , to which the ends of a toggle, N' , are jointed. This toggle is connected by means of a link, O , to a hand-lever, O' , pivoted to the frame. (See particularly Fig. I, in which the toggle and lever and their attachments are shown in dotted lines.) By means of this hand-lever the valves G' and H can be turned so as to admit the force of the explosion in the explosion-chamber H to either side of the connected pistons A' and B , and so reverse the direction of their rotation. The exhaust-pipe P , which leads from the exhaust-valve chamber H , extends to an exhaust-box, P' , around the shaft a' , and the gases resulting from the explosion pass through holes s into the said shaft, which is hollow, and out at its open end. The exhaust-pipe is made to extend to a point considerably above the shaft, in order that when the engine is to be employed in the propulsion of a vessel, and is situated below the water-line, the water cannot reach the moving parts of the engine. The water-line in this case would be indicated by the dotted line y y .

Supposing the various parts of the machine to be in the relative positions shown in the drawings, the operation of the engine is as follows: To start the engine, the lever K is operated by hand through the medium of the arm n , which is furnished with a handle, s' , and is adapted in any suitable way to be, at will, moved independently of the shaft n' . When the lever K is vibrated, a proper quantity of fluid is at each stroke admitted to the explosion-chamber H' through the medium of the valves h h' , together with the requisite volume of air to support combustion, and the ignition is effected by the flame being drawn into the exhaust air-pump, when it meets with the explosive mixture, as before stated. The

explosive force passes to the valve-chamber G through the port f , and thence through the pipe F and the chamber C' and its branches d and e to between the pistons A' and B . It now acts directly on the teeth e' and forces the pistons in opposite directions, as shown by the arrows in Fig. I. When the teeth against which the explosive force acts pass around to the branches e' and f of the channel D , the exhaust takes place, and the spent gases escape through the pipe G to the exhaust-valve chamber H , and thence to the exhaust-pipe P . When it is desired to reverse the direction of the engine, the toggle is drawn over by means of the hand-lever O' , which has the effect of throwing the explosive force through the pipe F to the opposite side of the pistons, and allows the escape of the spent gases through the pipe F' to the exhaust-valve chamber.

I claim as my invention—

1. In a gas-engine, the combination of a casing, a pair of rotary pistons with interlocking teeth situated within the casing, an explosion-chamber in communication with the interior of the said casing, valves to control the admission of the explosive gases to and others to control the exit of the said gases from the said casing, and means to supply the explosive mixture to the said explosion-chamber, substantially as specified.

2. In combination with the explosion-chamber of a gas-engine, a pipe to admit hydrocarbon fluid or gas thereto, having valves and suitable mechanism to control its flow to the said chamber, an air-pump to force air to the said chamber, and an air-exhaust pump to draw in a flame and effect the explosion of the mixture in the said chamber, substantially as specified.

NATHAN E. NASH.
